TANK INSULATION

Charles E. Ernst, Elizabeth, N. J., assignor to
 Johns-Manville Corporation, New York, N. Y.,
 a corporation of New York

Application December 31, 1948, Serial No. 68,709

1 Claim. (Cl. 220—15)

1

The present invention relates to insulated structures and more particularly to improved insulating constructions for the side walls of tanks and the like.

Heretofore it has been proposed to insulate the walls of tanks used in the refining and storage of petroleum products and for other purposes, the prior installations comprising insulating blankets or slabs applied to the tank walls, and in some instances, covered by a weather-resistant sheathing supported from the tank wall by metal framing members. The principal object of the instant invention is the provision of an improved construction of this general type which will be free of any metallic, heat-conducting paths through the insulation and, at the same time, provide for the support of an outer sheathing while permitting the sheathing and tank to relatively contract and expand under varying temperature conditions.

Another object of the invention is the provision of an insulated construction including an insulating layer and an outer, weather-resistant sheathing, the latter being supported from the tank wall by structural members including thermal insulating blocks interposed between the sheathing and the tank wall, the supporting means being of a character to permit the tank and sheathing to relatively contract and expand without disruption of the weatherproofing characteristics of the sheathing.

Another object of the invention is the provision of a construction in which the sheathing is laid in horizontal courses with the courses in overlapping or shingled relationship. The lower edges of the overlapping sheets are supported from the edges of the overlapped sheet, the supporting means allowing limited, relative shifting of the sheets.

My invention will be more fully understood and further objects and advantages thereof will become apparent when reference is made to the more detailed description of a preferred embodiment of the invention which is to follow and to the accompanying drawings, in which:

Fig. 1 is an elevational view showing a tank or the like in different stages of construction of the insulating cover;

Fig. 2 is a sectional view on an enlarged scale, taken on the line 2—2 of Fig. 1;

Fig. 3 is a sectional view on an enlarged scale, taken on the line 3—3 of Fig. 1;

Fig. 4 is a sectional view on an enlarged scale, taken on the line 4—4 of Fig. 1;

Fig. 5 is a view similar to Fig. 4 but showing a horizontal joint in the process of assembly;

2

Fig. 6 is a perspective view of a clip element employed in the formation of the horizontal joint;

Fig. 7 is a sectional view on an enlarged scale, taken on the line 7—7 of Fig. 1;

Fig. 8 is a sectional view on an enlarged scale, taken on the line 8—8 of Fig. 1;

Fig. 9 is a sectional view on an enlarged scale, taken on the line 9—9 of Fig. 1;

Fig. 10 is a perspective view of a stud splicing strip; and,

Fig. 11 is an exploded view of a stud and supporting elements.

Referring now to the drawings and first to Fig. 1, there is shown a tank 10 of the type conventionally employed for the storage of petroleum products and the like, and suitably composed of steel sheets riveted or otherwise secured together in any conventional manner.

In accordance with the instant invention, members 14 (see particularly Figs. 1, 2, 3 and 11) are secured to the tank wall in alignment to form vertical rows at intervals circumferentially of the tank, the spacing of the rows being determined by the number of stud members, later to be described, required to support the insulating cover. Members 14 may be either welded to the tank or, where this is not advisable, they may be secured by bands or cables extending circumferentially around the tank. The particular shape of the members may be varied but preferably is substantially that shown in Fig. 11 where a member 14 includes a forwardly projecting central section 16 having perforations 18 to receive fastening elements, the section 16 being integrally connected to lateral flanges 20 by side walls 22. Flanges 20 are adapted to rest against the tank wall and to be secured thereto by welding where such operation is permissible. To readily adapt the member to securement by banding where welding is not advisable, the flanges are extended beyond the central section to underlie the band, illustrated in dotted lines at 24. Members 14 support blocks 26 which are secured thereto by screws 28 passing through perforations 18 and with their heads received within the recess behind the central section 16. Blocks 26 are made of a strong, thermal insulating, board-like material. Suitably for this purpose an insulating material comprising highly compressed, densified, asbestos and binder compound is used. However, other known materials having relatively high strength and screw holding ability may be employed as desired.

Secured to the outer faces of the vertically aligned blocks 26 are stud sections 30, each con-

sisting of a channel member having rearwardly directed flanges 32, and a central recessed section 34. The stud sections are of a length for easy handling and suitably a number of them may be required to extend the height of the tank wall. The connection of the required number of sections for a full length stud is made by links 36 (see Figs. 7 and 10). Central recessed section 34 is provided with perforations 40 at locations opposite blocks 26 for the reception of screws 38, whereby the stud sections are supported from the blocks. The central recess 34 also serves as a drainage channel for any moisture which may penetrate between the sheathing joints. It will be appreciated that the block will be located at the juncture of stud sections (see Fig. 7). Also, blocks are placed adjacent the top and bottom of the tank to support the ends of the studs (see Figs. 9 and 8, respectively). The block at the bottom rests on an angle or the like 39. Suitably the sheathing extends somewhat below the block as shown in Fig. 8. The perforations 40 are of elongated shape to permit the stud sections to move vertically to a limited extent on screws 38 to allow for expansion and contraction of the stud section and/or the tank wall. Connecting member 36, previously referred to, is placed behind the adjacent ends of the stud sections and secured to one by the screws 38 which enter the block and to the other by bolts 42.

The entire area of the tank wall, except where interrupted by blocks 26, is covered by suitable insulating material 44. For this purpose blocks of magnesia insulation of a thickness to fit between the tank wall and the inner ends of flanges 32 may be secured in any suitable or conventional manner, such as by banding. Other blanket or panel type insulations of known types are also suitable.

The insulating layer is protected against the weather by an outer sheathing 46 consisting of a plurality of courses of sheets 48 laid in horizontal, overlapping or shingled arrangement (see Figs. 1, 4, 5 and 7). The sheets may be of any suitable, weather-resistant, moisture-proof, permanent material, a hardened, compressed, asbestos-cement composition being preferred as it has been found to be ideally suitable for this purpose. The sheets are arranged to have their vertical joints overlie studs 38 (see Fig. 3) and are secured thereto by means now to be described. It will be appreciated that ordinarily the sheets will span more than one stud space, as illustrated in Fig. 1, so that the joints will normally be only on alternate studs. Overlying the edges of the sheets at the joints are vertically extending battens 50, suitably composed of a hardened, compressed, asbestos-cement material of the same type as that of which the sheets are made. The battens are in sections of lengths approximately corresponding to that of the vertical dimension of the sheets and their ends are overlapped as illustrated. Sheets 48 are spaced apart at the joints, as shown in Fig. 3 to allow for expansion and contraction and are held against the studs by the batten strips. The latter are secured to the studs by suitable fastening devices, such as sheet metal screws 52, which project between the edges of the sheets and into the recessed central section of the stud.

The horizontal edges of the sheets are secured by clips 54 (see particularly Figs. 4 and 5), the clips being placed at suitable intervals. Clips 54 are of L-shape and include a leg 56 and flange 58, the latter being of a width slightly greater than the thickness of the material of the sheets. The clip is perforated at 60 to receive a fastener such as a sheet metal screw 62. In assembling the sheets of each course, the clip 54 is placed in position, as illustrated in Fig. 5, with screw 62 driven far enough into the perforation 60 to just hold the clip in position. The overlapping sheet is then slid downwardly on the overlapped sheet until screw 62 contacts the upper edge of the overlapped sheet. Screw 62 is then tightened to firmly bind the sheets together under the spring tension of the clip.

The construction described above provides complete insulation of the tank wall while fully protecting the insulation from the weather. The special features of the construction which permit relative movement of the tank and the sheathing insure that different rates of contraction and expansion of the tank or of the elements of the insulating cover will not cause buckling or loss of weather-tightness of the sheathing. Also, there are no through metal paths for heat-conduction through the insulation.

Having thus described my invention in rather full detail, it will be understood that these details need not be strictly adhered to but that various changes and modifications may suggest themselves to one skilled in the art, all falling within the scope of the invention as defined by the subjoined claim.

What I claim is:

In an insulated structure for a tank wall, an elongated stud section extending vertically of the wall, supporting members secured to the tank wall, insulating blocks between the members and stud section adjacent the ends of the latter, fastening means extending through said members into said blocks, elongated openings in the stud section opposite the blocks receiving fasteners extending through the stud section and into the blocks, weather-resistant sheets with their horizontal edges in overlapping relationship, horizontally adjacent sheets forming joints on said stud section, means securing said sheets to said stud section while allowing horizontal movement therebetween, and means securing the overlapping edges of the sheets to allow vertical movement thereof.
